UNITED STATES PATENT OFFICE.

THOMAS W. HOLT, OF ELKHART, INDIANA, ASSIGNOR TO CURTAIN SUPPLY COMPANY, OF ELKHART, INDIANA, A CORPORATION OF ILLINOIS.

SASH GUIDE.

Application filed May 25, 1925. Serial No. 32,535.

This invention pertains to sash guides, and has for its object the provision of a guide in the form of a box-like rib having spring separated side walls which are adapted to be embraced between the side walls of a groove in the stile of a sash.

The guide of the invention is light, rigid and durable in construction, is inexpensive to manufacture, may be readily attached to or removed from the jamb of a window, and has many other good features which those skilled in the art will appreciate.

Two slightly different structural embodiments of the invention are presented in the accompanying drawing and following description for the purpose of exemplification, but the invention is of course susceptible of application in other variously modified embodiments coming equally within the spirit of the invention as the same is defined in the appended claims.

In the drawing:

Fig. 1 is a view of a corner of a window sash associated with a guide constructed in accordance with the invention:

Fig. 2 is an interior view of one form of the guide;

Fig. 3 is a transverse section taken through the sash and guide at one point;

Fig. 4 is a similar section taken at another point;

Fig. 5 is an interior view of another form of the guide; and

Fig. 6 is a transverse section taken through the sash and guide, in that form of the latter shown in Fig. 5.

Referring in detail to the drawing, and particularly to Figs. 1, 2, 3 and 4 thereof, one will observe that the guide of the invention is fixedly attached to the jamb 10 of an associated window, and is slidably embraced between the side walls 11 of a guide groove in the stile 12 of an associated sash.

The guide consists of a rigid angle strip 13 which is attached to the jamb 10 by means of a number of machine screws 14, a second rigid angle strip 15 of smaller size which is slidably secured to the strip 13 by means of a number of pin and slot connections 16 between the lapped flanges 17 and 18 of the strips, and a number of bowed leaf springs 19 carried by one of the strips and bearing against the other to separate the flanges 20 and 21 of the strips and cause the same to expand against the side walls 11 of the stile

12. Suitable spacing sleeves 22 are positioned about the screws 14 between the flange 17 of the strip 13 and the jamb 10 to position the strip 13 in proper relation to the jamb, and the flange 18 of the strip 15 may be cut away at 23 adjacent the sleeve 22 to prevent the sleeves from interfering with the lateral movement of the strip 15 relative to the strip 13.

The construction above described presents a box-like rib which is contained inconspicuously within the groove in the stile of the associated sash and is provided at its opposite sides with two spring separated sash-engaging portions for contiguous weather-proofing engagement with the sash throughout the vertical extent of the latter.

In Figs. 5 and 6 of the drawing is shown another form of the guide which differs from the form above described only in that a number of coil springs 24 are substituted for the bowed springs 19.

I claim:

1. The combination with a sash having a guide groove in one edge thereof, of a sash guide, comprising two associated strips having two sash-engaging portions on the opposite sides thereof which extend the full height of the sash and together constitute a rib for reception in the groove of the sash, and spring means acting between the strips to separate the sash-engaging portions, one of the strips being adapted to be fixedly attached to a window jamb.

2. A guide comprising a strip adapted to be fixedly attached to a window jamb, a second strip arranged in laterally shiftable relation to the first strip, two sash-engaging portions of substantially equal length on opposite sides of the strips, and spring means acting between the strips to separate the sash-engaging portions.

3. A guide, comprising a strip adapted to be fixedly attached to a window jamb, a second strip carried by the first strip in laterally shiftable relation thereto, two sash-engaging portions of substantially equal length on opposite sides of the strips, and spring means acting between the strips to separate the sash-engaging portions.

4. A guide, comprising a strip adapted to be fixedly attached to a window jamb, a second strip carried by the first strip in laterally shiftable relation thereto, two sash-engaging portions of substantially equal

length on opposite sides of the strips, and spring means carried by one of the strips and acting against the other to separate the sash-engaging portions.

- 5. A guide, comprising an angle strip adapted to be fixedly attached to a window jamb with one flange of the strip perpendicular to the jamb to engage with the sash and the other flange in parallel relation to the jamb, a second angle strip arranged with one flange of the strip perpendicular to the jamb to engage with the sash and the other flange in lapped relation to that of the first strip, and spring means acting between the sash-engaging flanges of the strips to separate the same a limited distance.
- 6. A guide, comprising an angle strip adapted to be fixedly attached to a window jamb with one flange of the strip perpendicularly abutting the jamb to engage with the sash and the other flange in spaced parallel relation to the jamb, a second angle strip carried by the first strip with one flange of the strip perpendicular to the jamb to engage with the sash and the other flange in lapped relation to that of the first strip,

pin and slot connections between the lapped flanges of the strips to permit the sash-engaging flanges to be separated a limited distance, and spring means acting between the sash-engaging flanges of the strips to separate the same.

7. A guide, comprising a rigid angle strip adapted to be fixedly attached to a window jamb with one flange of the strip perpendicularly abutting the jamb to engage with the sash and the other flange in spaced parallel relation to the jamb, a second rigid angle strip of smaller size carried by the first strip in spaced relation to the jamb with one flange of the strip perpendicular to the jamb to engage with the sash and the other flange in lapped relation to that of the first strip, pin and slot connections between the lapped flanges of the strips to permit the sash-engaging flanges to be separated a limited distance, and bowed leaf springs acting between the sash-engaging flanges to separate the same.

In testimony whereof I have hereunto subscribed my name.

THOMAS W. HOLT.
